(57) **CLAIM**

The ornamental design for a projector embedded in walls and ceilings, as shown and described.

DESCRIPTION

FIG. 1 is a perspective view of a projector embedded in walls and ceilings;

FIG. 2 is a top view thereof;

FIG. 3 is a bottom view thereof;

FIG. 4 is a front view thereof;

FIG. 5 is a rear view thereof;

FIG. 6 is left side view thereof;

FIG. 7 is a right side view thereof; and,

FIG. 8 is bottom perspective view thereof.

The broken lines showing portions of the projector embedded in walls and ceilings form no part of the claimed design.
